ANTENNA CONSTRUCTION

John Wilson Shur, Sea Cliff, N. Y., assignor to
 Shur-Antenna-Mount Inc., Sea Cliff, N. Y., a
 corporation of New York

Application December 29, 1944, Serial No. 570,297

9 Claims. (Cl. 250—33.65)

1

This invention relates to improvements in antenna construction particularly adapted for use in connection with television and frequency modulation.

Various types of antenna arrangements have been proposed for the sending and reception of radio signals of the type referred to, but for the most part they are either too complex and expensive, they are difficult to manufacture and set up under normal circumstances, or they do not possess enough flexibility in their adjustment for an optimum tune-up process.

The necessity of varying the amplitude of an antenna, as appreciated in the art, makes it highly desirable to make as many factors as possible easily changeable with respect to each other in order to provide an optimum "tune-up."

The primary object of this invention is, therefore, to provide an improved antenna construction which is simple and inexpensive to make, and which embodies features of flexibility and adjustability so necessary for optimum signal strength.

A further object of the invention is to provide an antenna arrangement of "knock down" construction which can be assembled and set up with a minimum of time and experience.

Another object of the invention is to provide an antenna unit which is readily mounted in a variety of circumstances and on various types of support.

A still further object of the invention is to provide a fully insulated antenna construction in which the antenna elements are readily adjustable in several ways for maximum signal strength.

An important feature of the invention is a dipole antenna arrangement in which each element is supported in a plurality of insulator members which are rigidly mounted in such a way as to avoid sagging of the elements. A preferred form of antenna construction of the present invention comprises a pair of metal elements such as tubes of predetermined length mounted end to end in alignment and in spaced relation, each element being supported in a pair of spaced insulator members or blocks mounted on a supporting member or on a bracket of special construction. In one form the support is a relatively long round member on which the insulator blocks are slid to place, each insulator block having a hole to fit the support and a hole to receive the metal element or tube which is mounted parallel to the support, the support being rotatable for changing the angle of radiation when the unit is used in an antenna array.

2

Other objects, features and advantages of the improved antenna of the present invention will be apparent to those skilled in the art from the following detailed description taken in connection with the accompanying drawings forming a part of this application.

Fig. 1 is a plan view looking down, of one embodiment of the improved antenna of the present invention, with parts broken away.

10 Fig. 2 is an end elevational view of the construction shown in Fig. 1.

Fig. 3 is a side view looking from the left, of the antenna bracket construction shown in Fig. 1.

15 Fig. 4 is a perspective view of a modified form of the antenna construction of the present invention.

Fig. 5 is a side elevational view of a form of the improved adjustable antenna of the present invention particularly adapted for quick and easy fabrication assembly, tuning, and take down.

20 Fig. 6 is a cross-sectional view taken on the line 6—6 of Fig. 5, showing the construction of the insulator blocks.

25 The antenna construction shown in Figs. 1 to 3 comprises a wood cross piece 10 usually of from four to six feet in length which is mounted on a mast, tower, the roof of a house, or some other suitable object above ground. At predetermined spaced points on the cross piece 10 are mounted 30 metal brackets 12 for supporting the antenna elements, one only of the brackets being shown to simplify the illustration. The bracket 12 is preferably made of a single piece of plate metal such as aluminum, copper, stainless steel or other suitable material, pressed and cut into the cross-shaped form shown in Fig. 1, comprising side projections 14 and end projections 16. Each of the side projections or extensions 14 include a pair of spaced upright sections 18 which may be connected and strengthened by an integral web 20. Each of the end sections 16 include a pair of spaced upright flange members 22 parallel to the members 18 and extending along the sides of the extensions 16.

40 45 In Figs. 1 to 3, antenna elements 24 of a dipole antenna which may be metal tubes or rods, are supported above the base of the bracket 12 by means of a short insulator block 26 of Micarta or other suitable insulation, bolted to the upright members 18 of each extension 14, and long insulator blocks 28 of similar material bolted to the upright flanges 22 in the manner shown. The substantially spaced blocks 26 and 28 are mounted in parallel and provided with suitable 50 55 holes to receive the elements 24 and hold them

in alignment and spaced from any metal of the bracket 12. The elements 24 are held in place in adjusted or tuned spaced relation to each other by means of cotter pins 30 and screws 32, the latter of which also serve to attach a transmission wire 34 to the inner end of each element 24. The elements 24 are usually from one to two inches apart. The wires lead to a receiver or to a transmitter, as desired. The pins 30 are adjacent the outside of the blocks 26 to permit quick assembly.

The antenna arrangement as described above is a dipole center-fed element or unit which is mounted opposite and parallel to a director or reflector element (not shown), mounted on the other end of the cross piece 10. The director or reflector element is constructed the same as the dipole element shown, except that a single long metal tube or rod is used, in place of the two elements 24, which extends through all of the insulator blocks 26 and 28, and there are no connecting wires. It is to be understood that the combined length of the elements 24 and their size and spacing from the reflector will, at least in part, be determined by the location, and the character and wave length of the signals to be received or transmitted, as understood by those skilled in the art. While Micarta is preferred for the blocks 26 and 28, other suitable insulating material may be used.

In making the bracket 12 a flat piece of metal is preferably cut to shape, and punched with the necessary holes, in a single operation, while the bending of the upright flanges 18, 20 and 22 may be readily performed in another operation. Holes are preferably provided, as shown, in sections 14 as well as in 16, since it may be desirable to mount the bracket otherwise than on the cross piece 10. The bracket or brackets 12 of any given antenna unit may be mounted in any necessary or desired position such as beneath a cross beam or support, since the elements 24 will be fully supported by the spaced blocks 26 and 28 constituting a complete rigid unit which can be supported in any position or angle.

The antenna construction shown in Fig. 4 is similar to that of Figs. 1 to 3, except that a different form of insulator arrangement is employed, the metal bracket 12 being the same except that the flanges 22 may be omitted if desired. In this form, the antenna elements 24 are mounted in oval topped blocks of insulation 36 which are fastened to the top of the extensions 14 by means of screws. Screws also fasten the remote ends to the members 18. The blocks 36 may be of Micarta or other insulation, and each preferably extends the full length of the extensions 14, or more, so long as there is ample spacing between the inner ends of the elements 24, which are fixed in adjusted position in the holes in the blocks 36 by means of pins or set screws 38 in the top of the blocks 36. The elements 24 are mounted in alignment and in tuned spaced relation to the end members 18 and 20.

Fig. 5 illustrates a highly desirable form of antenna construction which may be made in "knock down" form and quickly assembled at the point of use by anyone familiar with tuning. For purposes of illustration, a dipole antenna is shown mounted in front of a mast, post, or upright 40 which is set in a tubular mast holder 41. The mast 40 is provided with a horizontal hole in which a cross piece 42 of from four to six feet long is secured by means of a pin or set screw 43. Near each end of the cross piece 42 a horizontal hole is provided, and a support member 44 is centered and secured therein, as for example, by means of

a pin or set screw 46. The members 40, 42 and 44 may be of wood such as maple, preferably impregnated with a resin preservative, and preferably of circular cross section, as indicated, for members 5 42 and 44, to facilitate fabrication and assembly.

The dipole antenna unit of Fig. 5 is mounted on the near end of the cross piece 42, as shown, while a director or reflector unit (not shown) is mounted on the opposite end. The member 44 10 carries four similar Micarta or other insulator blocks 48 and 50 which are punched or bored to slip on, as shown in Fig. 6. Each block is fastened in place by a pin or set screw 52 which contacts or passes through a hole in the member 44, 15 the blocks being in a straight line. The lower portions of the blocks 48 and 50 are provided with holes for receiving antenna elements in the form of rods or tubes, such as the tubes or pipes 54 which are similar to the elements 24. The inner 20 ends of the tubes 54 are spaced from each other in adjusted position as in Figs. 1 and 4, and each is connected to a transmission wire 56, the end of each wire being soldered to a washer 58, larger than the tube 54, which is held onto the end of the tube by a screw set in the tapped end of the tube. 25 The washers 58, together with cotter pins 60, outside the blocks 48, keep the tubes 54 in place and provide for a quick assembly. The distance between the inner ends of the tubes 54 may be adjusted for impedance during tuning by moving the blocks 48 and 50 on the beam 44.

The mast 40 may be rotated so as to change the angle of the elements 54, and that of the reflector, with respect to the source of radio signals and held at the desired angle in the holder 41 by the set screw, as shown, or by other means. Furthermore, the elements 54 may be mounted above or in front of the supporting member 44 by rotating the member 44 in the member 42 and setting the screw 46, and thereby change the angle of radiation of the complete antenna, or the angle of reception with respect to ground. For this purpose the axis of the members 44 and 54 may be from two to four inches apart, which provides for an adequate range for tuning since the beam 44 may be rotated up to 180°. In some cases, the tuning of an antenna requires the altering of the relative angle of the antenna to ground and this is accomplished in the present construction when employed in a multi-element antenna by rotating the beam 44 on its axis and setting the screw 46. In an extreme case the antenna elements 54 may be directly above the beam 44, while at the opposite end of the cross member 42 the antenna element may be directly below the beam 44. The relative rotation of the beams 44 may also be used in obtaining the final spacing between the two antenna units, as between dipole and reflector elements. One end of the cross member 42 may have a series of holes for the beam 44 to provide for proper spacing in tuning.

Where tuning conditions demand it, the polarization of the antenna, the plane of reception or transmission, can be readily changed from horizontal radiation or reception to vertical, or other necessary angle, by rotating the cross member 65 42 in the hole in the mast 40 and setting the screw 43. This rotation swings or rotates the entire antenna assembly without disturbing the other 70 adjustments referred to above. The antenna units of Figs. 1 and 4 may be rotated in the same way.

The improved antenna construction of the present invention is one in which maximum flexibility for tuning is provided and at the same time 75 is a relatively simple arrangement which is easy

to manufacture, assemble and transport. Furthermore, the "knock down" form is one which can be easily taken down and moved, or in which a part or element may be readily taken off for adjustment. In all forms of the device the insulators are spaced or mounted in such a way as to give rigid support for the elements and to reduce sagging to a minimum. The brackets of Figs. 1 to 4 may be of sufficient length for this purpose, while the relatively long beams 44 in Fig. 5 give exceptional support for the elements.

While the beams 44 and cross members 18 and 42 are conveniently made of wood, they may be made of metal such as pipe. Other changes may also be made without departing from the spirit and scope of the invention as defined by the claims.

What is claimed as new is:

1. An antenna unit comprising in combination a relatively long supporting member, a series of insulator members attached in spaced relation along said member and rotatably mounted radially with respect to the axis thereof, a long rigid metallic antenna element mounted in said insulator members in spaced relation to said supporting member, and means for fixedly securing said insulator members to said supporting member at the desired position.

2. An antenna unit comprising a relatively long supporting beam mounted at its intermediate section on a support, said beam being rotatable on its longitudinal axis with respect to said support, means for locking said beam with respect to said support, a plurality of insulator blocks attached in spaced relation along said beam, means for holding said blocks in fixed position and in alignment on said beam, and a straight metal antenna element mounted in said blocks in substantially spaced relation to said beam and substantially parallel thereto.

3. An antenna unit comprising an axially rotatable upright mast, a relatively long cross support mounted on top of said mast, said support being rotatable on its longitudinal axis, means for locking said support with respect to said mast, a beam on each end of said support for carrying spaced antenna elements in substantially parallel arrangement, a plurality of spaced insulators mounted along each beam, and a long metal antenna element attached to the insulators on each beam in spaced relation and substantially parallel to the beam.

4. An antenna unit comprising in combination a relatively long supporting beam, a support for said beam including means for mounting the beam so that it is rotatable on its axis with respect to said support, a series of insulator blocks attached in spaced relation along said beam and arranged in line, a long straight metallic antenna element attached to said insulator blocks, said blocks and element being rotatable with the beam about the axis of the beam when the beam is rotated on its axis with respect to the support, and means for securing the beam in fixed position with respect to the support with the antenna element in its tuned position.

5. In a dipole antenna unit, a supporting member, a relatively long supporting beam rotatably mounted on the supporting member, a plurality of insulator members attached in spaced relation along said beam on each side of its lengthwise

center and rotatably mounted radially with respect to the axis of the beam, a long rigid metallic antenna element mounted in the plurality of insulator members on each side of the lengthwise center of the beam and in spaced relation with respect to the beam, said elements being spaced endwise with respect to each other, means for securing the insulator members to the beam in alignment, and means for securing the beam against rotation with the antenna elements in the desired tuned position.

6. In an antenna as defined by claim 5 in which means are provided for adjusting the end to end spacing of the antenna elements.

7. A knockdown antenna construction comprising a relatively long supporting member having a circular bore at each end extending laterally through the member, a long beam of circular cross section extending through each of said bores and mounted therein for axial rotation in tuning the antenna, a plurality of relatively long spaced insulators on each beam each having a bore fitting the beam and through which the beam extends, each insulator mounted on each beam having a bore therethrough approximately parallel to and substantially spaced from the beam, a metal antenna element extending through the last mentioned bores in the insulators of each beam, and means for locking each beam with respect to the supporting member with the antenna element mounted thereon in the desired tuned position.

8. A knockdown antenna construction comprising a supporting member having a circular bore extending laterally through the member, a long beam of circular cross section extending through the bore and mounted therein for axial rotation in tuning the antenna, a plurality of relatively long spaced insulators each having a bore fitting said beam and through which said beam extends, each insulator having a bore therethrough approximately parallel to and spaced substantially from said beam, a metal antenna element extending through the last mentioned bores in the insulators, and means for locking the beam in the bore of the supporting member with the element in the desired tuned position.

9. A knockdown antenna as defined by claim 8 in which the insulators are mounted in alignment on the beam, a rigid antenna element mounted in the insulators, means for securing the insulators to the beam and means for retaining the element in position in the insulators.
